UNITED STATES PATENT OFFICE

WILHELM H. HEISINGER, OF BERLIN-ZEHLENDORF, GERMANY, ASSIGNOR TO REMINGTON RAND INC., OF BUFFALO, NEW YORK, A CORPORATION

PROTECTIVE STRIP FOR CARDS

Application filed May 12, 1931, Serial No. 536,902, and in Germany October 26, 1926.

This invention relates to protective strips or sheaths for cards, particularly record cards such as those used in visible index equipment.

5 The invention comprehends the provision of a card and a protective sheath for a marginal portion thereof having portions formed for interfitting engagement to detachably connect the sheath or strip with the card, 10 and is directed to the formation of longitudinally extending securing portions on a marginal portion of the card for engagement with complementary portions extending longitudinally of the strip or sheath.

15 In the drawings showing one embodiment of this invention:

Fig. 1 is a rear face view of a card having a sheath attached thereto in the manner provided by the present invention.

20 Fig. 2 is a cross-section taken on line 2—2 of Fig. 1.

A card 1 of any suitable character adapted particularly for use as a record card in visible index equipment or the like, has the 25 marginal portion 2 thereof offset longitudinally from end to end thereof at 3 and 4 respectively to provide longitudinally extending bead portions along the marginal portion 2 providing attaching beads or parts.

30 A protective sheath or strip 5 formed of celluloid or other transparent material has a fold at 6 arranged at the edge of the card along marginal portion 2 with front and rear fold portions 7 and 8 respectively, disposed over the front and rear faces of card 1 to enclose the marginal portion 2.

The fold portion 8 is formed with longitudinally extending offset portions 9 and 10 respectively, to provide complementary bead 40 portions extending longitudinally from end to end of said fold portion 8 to receive the attaching beads 3 and 4 respectively. By this complementary engagement of the beads 3 and 4 in offset portions 9 and 10, the protective sheath 5 is detachably secured to the marginal portion 2 of the card. The material from which the strip or sheath 5 is formed is suitable resilient material, so formed that the fold portions 7 and 8 normally tend to resiliently engage the front

and rear faces of the card, for resiliently retaining offset portions 9 and 10 in connected relation with attaching beads 3 and 4.

Additional record cards or signals may be inserted between the front fold 7 of the protective sheath and the face of card 1 along the marginal portion thereof, and due to the resilient gripping action of the sheath 5, they will be retained in the pocket formed between the front fold 7 and the card. This manner of connecting the sheath 5 to the card compensates for differences in expansion and contraction and at the same time prevents the sheath from being accidentally disengaged from marginal portion 2 of the card 65 by movement transversely thereof, but by springing rear fold 8 away from the rear face of the card, it will be seen that the sheath may be readily detached whenever desired.

The invention claimed is:

1. In combination, a card having a marginal portion formed to provide a longitudinally extending bead portion, and a folded sheath embracing said marginal portion and having a complementary bead portion for detachably retaining said sheath on said card.

2. In combination, a card having a marginal portion formed with an offset portion extending longitudinally thereof to provide 80 an attaching bead, and a folded strip of resilient transparent material enclosing said marginal portion and having the fold portions resiliently engaging opposite faces of said card along said marginal portion, one 85 of said fold portions having an offset longitudinally extending bead formed therein to receive said attaching bead in complementary relation and detachably retain said strip on said card.

In testimony whereof I affix my signature.

WILHELM H. HEISINGER.
